UNITED STATES PATENT OFFICE.

VICTOR DE KUBINYI, OF WASHINGTON, DISTRICT OF COLUMBIA.

DESIGN FOR A WALL-PAPER FRIEZE.

Application filed June 7, 1926. Serial No. 17,970. Term of patent 3½ years.

To all whom it may concern:

Be it known that I, VICTOR DE KUBINYI, a subject of the Kingdom of Hungary, residing at 1327 Fifteenth Street N. W., in the city of Washington, District of Columbia, have invented a new, original, and ornamental Design for a Wall-Paper Frieze, of which the following is a specification, reference being had to the accompanying drawing, forming part thereof.

The figure is a plan view of a continuous wall paper frieze strip shown in sections in order to clearly illustrate the design.

I claim:

The ornamental design for a wall-paper frieze as shown.

VICTOR DE KUBINYI.
